COMBINED COIN MAT AND ADVERTISING DISPLAY

Robert L. Mitchell, 2130 San Fernando Road,
Los Angeles, Calif.

Filed Oct. 22, 1959, Ser. No. 58,030

Term of patent 14 years

(Cl. D52—4)

I claim:

The ornamental design for a combined coin mat and advertising display, as shown.
